[57] CLAIM

The ornamental design for an exterior of a binder cover, as shown and described.

DESCRIPTION

FIG. 1 is a front elevational view of an exterior of a binder cover, in a closed position, embodying my design;

FIG. 2 is a rear elevational view thereof;

FIG. 3 is a left elevational view thereof;

FIG. 4 is a right elevational view thereof;

FIG. 5 is a top plan view thereof, the bottom plan view being a mirror image thereof;

FIG. 6 is a front elevational view of an exterior of a binder cover, in an open position, embodying my design;

FIG. 7 is a top plan view thereof;

FIG. 8 is a front elevational view of an exterior of a binder cover, in an open position, embodying a second embodiment of my invention;

FIG. 9 is a front elevational view of an exterior of a binder cover, in a closed position, embodying the second embodiment of my invention;

FIG. 10 is a right elevational view thereof, the left elevational view being identical to FIG. 3;

FIG. 11 is a top plan view thereof, the bottom plan view being a mirror image thereof;

FIG. 12 is a front elevational view of an exterior of a binder cover, in a closed position, embodying a third embodiment of my invention, the rear, left and right elevational views thereof being identical to FIGS. 2, 3 and 4, respectively;

FIG. 13 is a front elevational view of an exterior of a binder cover, in an open position, embodying the third embodiment of my invention;

FIG. 14 is an enlarged view of a portion of the exterior of a binder cover showing the texture of the material, it being understood that the pattern is common to all embodiments of my design; and,

FIG. 15 is an enlarged cross-sectional view along line 15—15 in FIG. 14.

For the sake of clarity, FIG. 15 only depicts the profiles of the textures nubs directly along line 15—15.

The broken lines representing indicia in FIGS. 12 and 13 are for illustrative purposes only and form no part of the third embodiment of the claimed design.
